UNITED STATES PATENT OFFICE

WILLIAM W. TOOKER, OF WICHITA, KANSAS

TRUNK ATTACHMENT

Application filed May 10, 1928. Serial No. 276,697.

The invention relates to baggage trunks, and has for its principal object the provision of means by which the articles packed in the trunk may be securely engaged to hold them 5 and prevent them from being tossed about in the trunk.

A further object of the invention is the provision of a frame adapted to engage the articles packed in a trunk and providing 10 clamping means engageable by the wall of the trunk to hold the frame in close relationship with the articles packed in the trunk to prevent them from being tossed about in handling the trunk.

15 The invention will be described in detail hereinafter and will be found illustrated in the accompanying drawings in which

Figure 1 is a top plan view of a conventional trunk showing the lid partly broken 20 away to disclose the attachment arranged within the trunk.

Figure 2 is a fragmental longitudinal sectional view on a plane indicated by the line 2—2 of Figure 1.

25 Figure 3 is a similar view on a plane indicated by the line 3—3 of Figure 1.

Figure 4 is a transverse sectional view on a plane indicated by the line 4—4 of Figure 1.

30 Figure 5 is a sectional detail on a plane indicated by the line 5—5 of Figure 2, and

Figure 6 is a sectional detail on a plane indicated by the line 6—6 of Figure 4.

In the drawings similar reference characters are used to designate corresponding 35 parts throughout the several views.

A conventional trunk is indicated at A and shows the attachment applied thereto, and comprising a frame 1 made up of a plurality of bars preferably made of suitable gauge

40 wire and having longitudinal and transverse members 2 and 3, respectively, said members being secured in any suitable manner where crossed and provided with downwardly undulated portions 4 and 5, respectively, between the junctions of said wires 2 and 3, said frame forming a cushioned structure to engage clothing or other articles in the trunk to hold them from movement by the instrumentalities to be hereinafter described.

45 Securable to the side walls of the trunk A

are ratchet members 6 and 7, the ratchet members 6 being provided with recesses 8 having ratchet teeth 9 on the inner walls of said recesses, while the side walls of the recesses are provided with oppositely disposed vertical grooves 10. Ratchet members

7 are provided with ratchet teeth 11 and an upstanding shoulder 12. 13 indicates a latch bar pivotally engaging members 7 as shown at 14 and engageable by a latch member 15

55 to close the entrance to said teeth 11. 16 indicates clamping bars adapted to engage the frame 1 and engageable at their ends by ratchet teeth 9 and 11, said clamping bars

16 being provided with laterally extending lugs or pins 17 that engage in the grooves 10, it being understood that by lifting the end 18 of latch bar 16 when released from the teeth 11 the end 19 of each bar 16 will be released from the teeth 9 and the bar may be raised or lowered to the position desired to clamp

frame 1, while by moving the bar 16 into horizontal position end 19 may engage one of the teeth 9 while the end 18 may be engaged by one of the teeth 11, and may be secured in

65 engaging and clamping position by latching the bar 13 by means of the spring latch 15. The end 18 of each clamping bar 16 is provided with an upturned lug 20 that extends

70 into a groove 21 at the rear of teeth 11 to securely engage the end of the bar with said teeth. When the device is in the position shown in the drawings, the articles engaged by the frame 1 will be securely held from

75 movement in handling the trunk, the advantages of the invention being apparent in instances when the articles to be carried in the trunk are not sufficient to completely fill it as often occurs.

80 What is claimed is:—

1. A trunk attachment, comprising ratchet members adapted to be secured to the opposite side walls of a trunk, one of said ratchet members having teeth extending transversely of the trunk, grooved guide members arranged adjacent to said ratchet member, the other ratchet member having teeth extending longitudinally of the trunk, a clamping bar adapted to engage said ratchet members, a transverse pin on said clamping bar engaging

said grooved guide members and slidably mounting said clamping bar, a latch bar pivoted adjacent to the second mentioned ratchet bar to hold the clamping bar in engagement therewith, and a frame engageable by said bar and adapted to engage articles in the trunk.

2. A trunk attachment, comprising a ratchet member adapted to be secured to a wall of a trunk, said member being recessed, ratchet teeth on the inner face of the recess, the opposed walls of the recess having grooves therein, a clamping bar adapted to engage at one of its ends said teeth, transverse lugs on said clamping bar and engaging in said grooves, an upstanding lug on the other end of said clamping bar, a ratchet member adapted to be secured to the opposite wall of the trunk, the teeth of said ratchet member arranged at right angles to the plane of the teeth in the first mentioned ratchet member and adapted to engage the other end of the clamping bar, said ratchet member having a groove in the rear of the teeth aforesaid to receive said upstanding lug on the clamping bar, a latch bar pivotally secured to said ratchet member to hold the clamping bar engaged thereby, means to hold the latch bar in latching position, and a frame engageable by said clamping bar and adapted to engage articles in the trunk.

In testimony whereof I affix my signature.
WILLIAM W. TOOKER.
